UNITED STATES PATENT OFFICE.

JOHN SIAKEL, OF CHICAGO, ILLINOIS.

SANDPAPERING-MACHINE.

1,330,959.

Specification of Letters Patent.

Patented Feb. 17, 1920.

Application filed October 26, 1918. Serial No. 259,829.

To all whom it may concern:

Be it known that I, JOHN SIAKEL, a subject of the Emperor of Austria-Hungary, residing in the city of Chicago, in the county 5 of Cook and State of Illinois, have invented new and useful Improvements in Sandpapering-Machines, of which the following is a specification.

This invention relates to power driven 10 sand-papering machines arranged to sandpaper the edge of a single board or a plurality of boards and has among its objects to provide a novel machine of this character which shall be flexible and efficient in operation, and wherein the slidably movable work 15 table will be simultaneously moved in opposite direction to the movement of the revolving sand-papering rolls.

With these and other objects in view my 20 invention consists in the novel construction, combination, and relative position of the parts and members shown in the accompanying drawings, hereinafter described, and particularly pointed out in the appended 25 claims.

Referring to the drawing in which like reference characters indicate like or corresponding parts:

Figure 1 is a plan view of my preferred 30 form or construction embodying my invention. Fig. 2 is a sectional elevation taken on line 2—2 of Fig. 1 showing the revolving traveling sand-papering rolls. Fig. 3 is a cross section taken on line 3—3 of Fig. 1 35 showing the relative position of the sand-papering rolls and work table.

Fig. 4, is an end elevation taken on line 4—4 of Fig. 1.

Referring to the drawings, which show 40 one embodiment of my invention, I provide the stationary table 10 which is equipped with longitudinal tracks 11 upon which is slidably mounted for reciprocating movement the work-supporting frame 12. The 45 driving mechanism for the frame 12 includes the threaded drive shaft 13 which is located below the frame 12 and which extends longitudinally of the table 10 with the ends thereof supported in bearings 14 and 50 15^A. The frame 12 has operative connection with shaft 13 by means of the threaded sleeve 16 which is rigidly mounted to the bottom of the frame.

At one end of the shaft 13 I provide a

pair of loosely mounted bevel gears 17 and 55 18 arranged for alternate operative engagement by the jaw clutch 19 whereby said shaft 13 receives alternate reverse movements from the driving bevel gear 20 which is rigidly mounted upon the end of shaft 21, 60 which shaft 21 is propelled by a belt drive including a belt 22 passing over pulleys 23 and 24; the pulley 24 being provided with a friction clutch 25 so as to provide means for disconnecting the reciprocating frame driving machinery when the frame 12 is maintained in stationary position. The pulley 23 is rigidly mounted on the main drive shaft 26, which is propelled by the pulley 28 and belt 27 leading from any desirable source of 70 power.

The clutch operating lever 29, pivoted at 30 upon one side of the substantially square casting 15 which supports the ends of shafts 13 and 21, is formed with an arcuate rack 75 29^A having teeth in mesh with the pinion 31, the opposite side of which pinion is engaged by the teeth of the rack 32 formed at one end of the rod 33 which is slidably mounted in bearings 34 supported on one side of the 80 table 10. The frame 12 carries a rigid arm 35 through which the rod 33 passes and which arm 35 is arranged to engage either one of the lugs 36 rigidly mounted on rod 33. It is obvious that the longitudinal adjustment of the lugs 36 upon rod 33, controls the length of travel of the frame 12. In engaging either of the lugs 36, the rod 33 will shift the rack 32 and thus cause a rotation of pinion 31 and a movement of the underlying 90 rack 29^A and thus shift the clutch operating lever 29 so as to disengage the clutch 19 from either one of the gears 17 or 18. At this point of the operation, the movement of the frame 12 is stopped and would remain in 95 stationary position were it not for the weighted arm 37, (which is rigidly mounted on the end of shaft 38 which supports the pinion 31), which having passed a dead center, continues to move the shaft 38 by gravity, whereby the pinion 31 will cause a further movement of the rack 29^A and lever 29 so as to engage the clutch 19 with one of the gears 17 or 18 and thus continue the movement of the frame 12 in the opposite direction. 100

To facilitate the retaining of boards of varying width upon the frame 12, I provide

a retainer 39 which is perpendicularly disposed to the frame 12, and has laterally extending feet 39^A slidable within the grooves 12^A. Each foot 39^A is provided with a pair 5 of thumbscrews 41 for fastening the retainer to the frame at the desired distance from the abrasive rolls 40. Clamps or other means may further be added for rigidly securing the work to the frame 12.

10 Extending parallelly and adjacent to the table 10, is a base 42 having guides 43 within which is slidably mounted the abrasive roll-supporting frame 44. This frame 44 supports the two abrasive rolls 40, the 15 adjacent shifting rolls 45, and the idler rolls 46. The two abrasive rolls 40 are rigidly mounted upon spindles 40^A, the upper ends of which have slidable support within the top of the frame 44, and the lower ends of 20 which carry the rigidly mounted pulleys 47. The intermediate shifting roll 45 carries the comparatively smaller pulley 48 at the end of its spindle 49, but in this case the pulley 48 is loosely mounted and acts only as an 25 idler pulley for the drive belt 50 which extends from the end pulley 51 to the drive pulley 52. Fig. 1 shows the arrangement of the belt drive 50, wherein the idler pulley 48 intercepts the belt so as to deflect it 30 around same and thus afford arcuate contact with the two pulleys 47.

The two end shifting rolls 45 are provided with spindles 53, the lower ends of which and also that of spindle 49, carry the 35 chain sprockets 54, 55, and 56. A continuous chain 57 passes from the sprocket 54 to sprocket 56 and consequently is also engaged by the center sprocket 55. Below the sprocket 56 and also rigidly mounted to the 40 spindle 53 is another sprocket 57 which is operatively connected by a chain drive 58 to the smaller sprocket 59 mounted on spindle 40^A, which sprocket 59 is operatively connected to said spindle 40^A by means of an 45 extended key 40^B and is also rigidly connected to the adjacent pulley 47. The pulleys 47 are supported upon brackets 60, and one of the spindles 40^A having a collar 61 below the bracket 60 to prevent vertical 50 movement of pulleys 47.

The spindles 49 and 53 are supported in substantially square blocks 62 which are rigidly mounted in frame 44 against springs 63 retained by the cover plates 64.

55 The idler rolls 46 are loosely mounted on short spindles in a substantially rectangular frame 65 which is slidable in guides 44^A in the end horizontal cross members 44^B of the frame 44 responsive to the simultaneous rotation of the four screws 66 which have threaded connection through the four corners of the frame 65 and are loosely mounted in the frame 44.

60 The mechanism for simultaneous rotation 65 of the screws 66 whereby said frame 65 is

moved toward or from the abrasive rolls 40 includes a miter gear 67 on one end of each screw 66 in mesh with a miter pinion 68 mounted on a shaft 69 the other end of which carries a similar miter pinion 68 70 which also meshes with a miter gear 67 on the coöperative screw 66 at the other end of the frame. The upper and lower sets of screws 66 being interconnected by the miter gears 70 upon the vertical shaft 71 which is 75 provided with the operating hand crank 72.

In addition to the operation of the abrasive rolls 40 on work upon the frame 12, a stick of timber can be simultaneously sandpapered on the opposite side of the rolls 40 80 by insertion between the idler rolls 46 and the shifting rolls 45, which shifting rolls will gradually move such timber at a reduced speed due to the reduction in drive 58. In the sand-papering of such timber, as for 85 instance shown dotted and marked X in Fig. 3, it is desirable to first insert a timber Y of any suitable smaller cross section to act as a support, then upon the rotation of crank 72 simultaneously move the three idler or 90 presser rolls 46 toward the rigidly mounted shifting rolls 45, and with the timber X therebetween, until the face of timber X engages the abrasive rolls 40. It is now obvious that the pressure of springs 63 and 95 rotary movement rolls 45, is sufficient to overcome the dead weight of the timber X and move the same past the abrasive rolls 40.

The reciprocatory motion of the frame 44 in guides 43 of the base 42 is provided by a 100 mechanism similar to and coöperating with the driving mechanism for the frame 12, and includes a longitudinally extending threaded drive shaft 73 supported at one end in bearing 74 and at the other end in the cast gear support 75 at which point the shaft is also provided with spaced loosely mounted gears 76 and 77. These gears 76 and 77 are arranged for alternate engagement by the clutch 78 which is operated by the operating 105 lever 79 pivoted at 80 and carrying an arcuate rack 81 at the outer end where pinion 82 is engaged thereby. The pinion 82 mounted on shaft 89 and is adapted for operation by the rack 83 formed at the end 110 of bar 84, which bar 84 carries adjustable rigidly mounted lugs 85 arranged for alternate engagement by the arm 86 rigid on the frame 44. The shaft 89 is provided with a weight arm 90 similar to arm 37. It is 115 obvious that the frame 44 will receive a reciprocating movement through the described automatic reversing mechanism the operation of which is similar to that above described for the frame 12 and which in this case is driven by the gear 87 at one end of the shaft 21.

The arrangement of the machinery is such that the frame 12 always moves in opposite direction to the frame 44, and that by dis- 130

engaging friction clutch 25 the frame 12 can be retained in stationary position or by disengaging jaw clutch 88 the frame 44 can be held stationary. That is, either one or both 5 of the frames 12 or 44 can be held stationary.

As stated above the abrasive rolls 40 and shifting rolls 45 receive rotary motion from the belt 50 having connection with the drive pulley 52 which is mounted rigid to the top 10 of the vertical shaft 91 supported in the cast frame 92 and operatively connected to the main drive shaft 26 by bevel gears 93 and 94.

In order to impart a slight vertical movement to the rolls 40, simultaneously with 15 their rotation upon the spindles 40^A I provide a mechanism which consists of an oscillating arm 95 which is pivoted at 96 and which has forked ends 95^A arranged to embrace the collars 97 loosely mounted on the 20 spindles 40^A under the collars 98 which are rigidly fixed thereon. A link 99 connects one end of the oscillating arm 95 with the pin 100 on bevel gear 101 and which pin is arranged eccentric to spindle 102 which is 25 held in bracket 103. The bevel gear 101 receives its motion from the bevel gear 104 operatively mounted on spindle 40^A. Thus by the operation of belt 50, pulleys 47, the 30 spindles 46 will be revolved and simultaneously, through the bevel gears 104 and 101, and link 99, the oscillating arm 95 will transmit an alternate vertical movement to the

abrasive rolls 40 which are rigid upon spindles 46.

It is thought that the foregoing description and illustrations clearly disclose the construction and operation of the invention, hence a more extended explanation is omitted.

I claim:

1. In a sand-papering machine, the combination of a pair of parallel rotary perpendicularly reciprocating sand-papering rolls, guides, a movable support for said rolls mounted on said guides, means for reciprocating said support, a reciprocating work-supporting frame arranged for movement opposite in direction to said rolls, and means for arresting the movement of said roll support.

2. In a sand-papering machine, the combination of a pair of parallel rotary perpendicularly reciprocating sand-papering rolls, guides, a movable support for said rolls mounted on said guides, means for reciprocating said support, a reciprocating work-supporting frame arranged for movement opposite in direction to said rolls, and means for arresting the movement of said roll support or said frame.

In witness whereof, I have hereunto subscribed my name this 19th day of October, 1918.

JOHN SIAKEL.
